UNITED STATES PATENT OFFICE.

EVERETT H. BICKLEY, OF UPPER DARBY, PENNSYLVANIA.

AUTOMATIC PHONOGRAPH STOP AND START DEVICE.

Application filed March 31, 1921. Serial No. 457,413.

To all whom it may concern:

Be it known that I, EVERETT HUCKEL BICKLEY, a citizen of the United States, residing at Upper Darby, county of Delaware, State of Pennsylvania, have invented a certain new and useful Improvement in Automatic Phonograph Stop and Start Devices, of which the following is a full, clear, and exact description of the same, reference being had to the accompanying drawings.

The object of the invention is to provide a very simple and cheap device for operating the brake of a phonograph from movements and positions of the tone arm.

My invention provides a simple, compact, cheaply manufactured device which may be installed on practically any make of phonograph successfully provided the tone arm is driven from the record, and the record groove spiral ends in a closed ring or circle. When it is desired to start the phonograph using this device, the tone arm is swung to the extreme outer position momentarily, thus releasing the brake. When the tone arm has been carried by the spiral record groove to the inner circle, my device automatically releases the brake which stops the machine.

My invention is hereinafter more fully explained, and its characteristics set out in the claims.

In the drawings, Figure 1 is a plan view of my device, showing it applied to a phonograph, certain parts of the turn-table and tone arm being broken away to show the one method of application of my invention. Fig. 2 is a perspective view to a larger scale of the wheel and finger disc. Fig. 3 is a sectional elevation to larger scale of a finger, friction lever, and brake trip arm, with the plate, showing relative positions when operating. Fig. 4 is an enlarged view of an alternate construction of the fingers f^1 .

Referring to the parts shown in the drawings, a is a worm which is mounted on and driven by the center spindle b of the phonograph. c is the turn-table of the phonograph which is also mounted normally on the spindle b above the worm a . The sound record c^1 is shown on the turn-table c . A worm-wheel d is mounted rigidly on the shaft e and meshes with the worm a .

A finger-disc f is also mounted rigidly on the shaft e . The worm-wheel, shaft and finger-disc is mounted on bent up lugs on the plate g so that it is free to rotate about the

center of the shaft e , but is restrained from moving lengthwise of the shaft e . The friction lever H having a bifurcated end h and a pin extending downwards at h^1 is attached to the lever m by the friction joint k . This joint permits the lever H to lag behind the motion of the lever m when restrained by the sides g^1 and g^2 of the plate g or the action of the fingers f^1 . The lever m is mounted rigidly to the tone arm and moves with it. The tone arm n moves to the outer position n^1 carrying the lever m with it. The pin at h^1 now engages the arm q^2 on the lever Q and the lever Q moving about its fulcrum t stretches the spring r and removes the pressure between the friction pad s and the edge of the turn-table c^2 . The prong q^1 meanwhile latches behind the side g^1 holding the brake in the inoperative position. The tone arm is now swung in, and the selection on the record is played.

The friction lever H meanwhile rubs on the side g^1 and approaches the rotating finger disc f . After a portion of the record has been played the bifurcated end of the friction lever H engages with the fingers f^1 and is pushed away from the side g^1 a certain distance by each of the fingers f^1 . This motion taking place in a horizontal plane as shown in Fig. 3 by the dotted lines. The movement of the tone arm n and the lever m carry the friction lever H in the opposite direction to this "push" so that the rotating fingers f^1 will strike the slot h in the friction lever H as long as the tone arm is fed inwards. When the end of the record is reached, and the motion of the tone arm inward ceases, the lever H no longer moves inward so that the fingers enter the slot h , but the finger f^1 strikes the top of the friction lever H driving it downward against the lever Q which is unlatched thereby at q^1 from g^1 and the spring r applies the brake s at c^2 stopping the turn-table c . The friction joint k is weakly adjusted so that no load is put on the tone arm to speak of, and the side g^2 is provided to guide the friction lever H when the tone arm n swings back to the n^1 position. The plate g is suitably attached to the top of the phonograph by screws as shown or otherwise. If the stop is to be used in connection with records that are not a perfect spiral, or records that are drilled out of center, it is desirable to use the form of finger shown in Fig. 4. This finger is proportioned so that one revolution

of the turn-table is required from the time the leading edge of the finger f^1 clears the top surface of the friction lever H until the trailing edge of the finger f^1 clears the bottom surface of the friction lever H . The finger f^1 is also made to very closely fit the slot in the lever H on the trailing edge. This construction will operate perfectly on very defective records. Not limiting myself to the exact construction shown, as it is possible to obtain the same result by incorporating the friction joint in the tone-arm, and use a manually operated brake release, or it may be released by a cam on the tone arm, etc.

Having thus described my invention, what I claim and desire to secure by Letters Patent, is—

1. In a talking machine, comprising a driven turn-table, a reproducer coacting on a tone-arm, and a brake; the combination of a lever connecting with said tone-arm thru a friction joint, said lever being adapted to latch said brake at the extreme outer position of the tone-arm and unlatch said brake when the tone-arm has ceased to move at an inner position substantially as described.

2. In a talking machine comprising a driven turn-table, a reproducer coacting on a tone-arm and a brake; the combination of a slotted lever driven by said tone-arm thru a friction joint, with angular fingers driven at substantially right angles to the direction of motion of said lever, and guided at a certain position to engage the slot in said lever, pushing the end of said lever opposite to the direction of motion as carried by said tone-arm and friction joint, so that if said tone-arm fails to carry said lever back an equal amount before the next finger is presented, interference takes place, causing said lever to coact on brake to unlatch it, substantially as described.

3. In a talking machine comprising a driven turn-table, a reproducer coacting on a tone-arm and a brake; the combination of an angularly slotted lever driven by said tone-arm thru a friction joint, and fingers driven at substantially right angles to the direction of motion of said lever, and guided at a certain position to engage the slot in said lever, pushing the end of said lever opposite to the direction of motion as carried by said tone-arm and friction joint, so that if said tone-arm fails to carry said lever back an equal amount before the next finger is presented, interference takes place, causing said lever to coact on brake to unlatch it, substantially as described.

4. In combination with a sound reproducing machine having a driven turn-table a reproducer coacting on a tone-arm, an automatic stop and start mechanism comprising a lever carried by and connected with said tone-arm by means of a friction joint at

one end and having an angular slot in the other end of the said lever, a rotating finger disc, and means for driving said disc from the turn-table, means for guiding said slotted end of said lever into engagement with said disc at substantially inner positions of the said tone arm, a brake application lever extending transversely of the slotted end of said lever and adapted to unlatch the brake upon interference of the said fingers and said slotted end of the said lever, a projection from said slotted lever to engage a brake latching lever at extreme outer positions of said tone arm, a spring for applying said brake when unlatched by said interference, substantially as described and shown in the drawings.

5. In combination with a talking machine comprising a driven turn-table record support, a reproducer connected with a pivoted tone-arm, adapted to be fed laterally by the said reproducer following the grooves in the said record, and a brake; a bifurcated lever fastened yieldingly with a friction joint to said tone-arm, driven fingers adapted to contact with one leg of the bifurcated portion to push said friction lever opposite to the direction of feed of the said tone-arm, the length and position of said levers so proportioned that said contacting takes place only when said tone-arm is within the area in which records are completed, also the other or second leg of the bifurcated portion of said friction lever so constructed as to interfere with the motion of the said fingers unless said friction lever is moved from the position into which it was pushed by the contacting of the fingers with the first leg of the bifurcated portion, by the motion of the tone-arm following the record groove, a brake unlatching lever so positioned that the said interference will cause it to unlatch and apply the brake, to cause the stoppage of the turn-table substantially as described.

6. In combination with a talking machine comprising a driven turn-table record support, a reproducer connected with a pivoted tone-arm, adapted to be fed laterally by the said reproducer following the grooves in the said record, and a brake; a frictionally jointed lever carried by said tone-arm into correlation with a driven member whereby said lever is displaced backward periodically as long as said lever is fed forward by said tone-arm, said backward displacement being sensibly equal to the forward motion, also whereby said lever is displaced at right angles to the direction of feed, thereby releasing said brake when said tone-arm fails to cause said forward feed, substantially as described.

7. In combination with a talking machine comprising a driven turn-table record support, a reproducer connected with a pivoted tone-arm adapted to be fed laterally by the

5 said reproducer following the grooves in the said record, and a stop mechanism adapted to unlatch a brake mechanism when said tone-arm ceases to be fed laterally by said
 10 reproducer; a lever connected with said brake mechanism transversely positioned with reference to the stop mechanism, a pin carried on said stop mechanism adapted to engage said lever to latch-up said brake at the extreme outer position of said tone-arm substantially as described.

15 8. In a talking machine, comprising a driven turn table, a reproducer coacting on a tone arm, and a brake; the combination of a lever connecting with said tone arm thru a friction joint, said lever being adapted to unlatch said brake after the said tone arm has ceased to move, substantially as described.

20 9. In a talking machine, comprising a driven turn table, a reproducer coacting on a tone arm, and a brake; the combination of a lever connecting with said tone arm thru a friction joint, said lever being adapted to unlatch said brake after the said tone arm has decreased in speed, substantially as described.

25 10. In a talking machine, comprising a rotating element, a feeding element and a brake element; a brake releasing element cooperating with said feeding element and a repositioning element, cooperating with said rotating element, to periodically reposition said brake releasing element backward in relation to the feed into a subsequently interfering position with said repositioning element, the action of said repositioning element on said brake releasing element beginning and ending at substantially the same positions of the rotating element, and said interference adapted to cause the application of said brake element, substantially as described.

30 45 11. In a talking machine comprising a rotating element, a feeding element, and a brake element and a repositioning device; a means for applying the brake after the feeding element has ceased to feed, which means is coacted upon by the feeding element and periodically repositioned by the repositioning device, said time of repositioning beginning and ending substantially with the same relative position of the rotating element, substantially as described.

50 55 12. In a talking machine comprising a rotating element, a feeding element, a repositioning device and a brake element; a means for applying the brake element after the feeding element has decreased in feed, which means is coacted upon by the feeding element and periodically repositioned by the repositioning device, said time of repositioning beginning and ending substantially with the same relative position of the rotating element, substantially as described.

13. In a talking machine comprising a rotating element, a feeding element and a dynamic wedging brake element; a means cooperating with said feeding element for releasing said dynamic wedging brake element 70 when said feeding element has been moved to the starting position substantially as described.

14. In a talking machine comprising a rotating element, a feeding element, a dynamic 75 wedging brake element and automatic stop mechanism; a means for releasing said dynamic wedging brake element, and resetting said automatic stop mechanism when said feeding element is moved to the starting position substantially as described.

15. In a talking machine, comprising a rotating element, a traveling element and a brake element, the combination of a periodic trip mechanism for causing the application 85 of said brake element, and means for rendering the said periodic trip mechanism inoperative by the motion of said traveling element, and means for releasing the action of said brake element when said traveling element is moved to the starting position, substantially as described.

16. In a talking machine, comprising a rotating element, a traveling element and a brake element, the combination of a periodic 95 trip and repositioning mechanism for causing the application of said brake element, said trip mechanism being rendered inoperative by the motion of said traveling member, the beginning of said trip action and ending 100 of said repositioning action taking place at substantially the same relative position of said rotating element, substantially as described.

17. In combination, a rotating member 105 and a traveling member, a brake element, and a lever cooperating with said brake element and carried by said traveling member and acting after the traveling member stops to render said brake element operative, substantially as described.

18. In combination, a rotating member, a traveling member, a brake element, an oscillative lever carried on said traveling member cooperating with said brake element and acting after the traveling member decreases in speed to render operative said brake element, substantially as described.

19. The combination with a rotating member and a traveling member propelled thereby, and a brake member, of a normally inoperative brake unlatching mechanism for the rotating member, a floating member carried on said traveling member, movable periodically in opposite directions by the said unlatching mechanism and traveling members respectively, the said floating member being adapted to unlatch said brake member after failure of the said traveling member to move said floating member, under the ac- 120 125 130

tion of said mechanism, substantially as described.

20. The combination with a rotating member and a traveling member propelled thereby, and a brake member, of a normally inoperative brake unlatching mechanism a floating member carried by said traveling member movable periodically in opposite directions by the said unlatching mechanism and 10 traveling members respectively, the said floating member being adapted to unlatch said brake member under the action of said mechanism after failure of the said traveling member to move said floating member, 15 the reversals of said movement of said floating member occurring at substantially the same position of the said rotating member, substantially as described.

21. The combination with a rotating member and a traveling member, and a brake member of a normally inoperative brake unlatching member for the rotating member carried on said traveling member, movable periodically in opposite directions by the 25 said rotating and traveling members respectively, the said member being adapted to unlatch said brake member after failure of the said traveling member to move said unlatching member, and means for resetting and 30 latching up said brake member by movement of said traveling member to the starting position, substantially as described.

22. In a brake mechanism, comprising a rotating member, a traveling member and a 35 dynamic wedging brake member, the combination of a means for rendering the said dynamic wedging brake member inoperative on said rotating member by motion of said traveling member to the starting position and for causing the application of said 40 brake after the said traveling member has ceased to travel, substantially as described.

23. In a brake mechanism, comprising a rotating member, a traveling member and a 45 dynamic wedging brake member; the combination of a means for rendering the said dynamic wedging brake member inoperative on said rotating member by motion of said traveling member to the starting position, 50 and for causing the application of said dynamic wedging brake member after said traveling member has decreased in speed of travel, substantially as described.

24. In a talking machine comprising a rotating element, a feeding element and a 55 brake element, an oscillating element frictionally fed by said feeding element and periodically repositioned in exact relation to said feeding element, an unlatching member 60 operated synchronously with said rotating element and adapted to interfere with said oscillating element to cause unlatching of said brake element, substantially as set forth.

25. In a brake mechanism the combination 65 with a brake, of two independently

moving members, a brake unlatching member carried on the one and adapted to be oscillated periodically by the alternate action of said moving members, said unlatching member being adapted to cause the application of said brake member upon the failure of said moving members to oscillate said unlatching member and to cause the release of said brake member by the reverse motion of one of the said moving members, substantially as described. 70 75

26. In a brake mechanism, the combination with a brake, of a rotating element and a traveling element; a brake unlatching member carried by said traveling element to 80 be oscillated periodically by the alternate action of the said rotating element and the said traveling element, said unlatching member being adapted to cause the application of said brake member upon the failure of 85 said traveling member to cause said movement, the reversals of said oscillative movement occurring at substantially the same relative position of the said rotating element. 90

27. In a talking machine comprising a rotating element, a traveling element and a brake element, the combination of a brake releasing element, cooperating with said traveling element, a means for operating 95 said brake releasing element at periodic intervals, and a means for preventing the operation of the said brake releasing element by movement of the said traveling element, each reversal of movement of the said brake releasing element beginning and ending at substantially the same relative position of the said rotating element, substantially as described. 100

28. In a talking machine comprising a rotating element, a traveling element and a brake element, the combination of a brake releasing mechanism, a means for operating said brake releasing element at periodic intervals, and a means for preventing the operation of the brake releasing mechanism by movement of said traveling element, and means for resetting said brake releasing mechanism by movement of said traveling element to the starting point substantially as described. 105 110 115

29. In a talking machine comprising a rotating element, a traveling element and a brake element, the combination of a brake releasing member, carried on said traveling member, a means for operating said brake releasing member at periodic intervals, and a periodic means for preventing the operation of the brake releasing member by movement of said traveling element, each reversal of movement of the said brake releasing member beginning and ending at substantially the same relative position of the said rotating element, and means for resetting said brake element by movement of said 120 125 130

traveling element to the starting point, substantially as described.

30. In a brake mechanism, the combination with a brake member, of a rotating element and a traveling element, a brake unlatching member carried on said traveling element adapted to be oscillated periodically by the alternate action of the said rotating element and the said traveling element, said unlatching member being adapted to cause the application of said brake member upon the failure of said traveling element to cause said movement, the reversals of said oscillative movement occurring at substantially the same relative position of the said rotating element, and means for resetting said brake member by movement of said traveling element to the starting point, substantially as described.

20 31. In a talking machine comprising a rotating element, a feeding element and a brake element, an oscillating element frictionally fed by said feeding element and periodically repositioned in exact relation to said feeding element, as set forth.

32. In a talking machine, comprising a rotating element, a traveling element and a brake element, the combination of a periodic trip mechanism for causing the application of said brake element, and means for rendering the said periodic trip mechanism inoperative by the motion of said traveling element, said means beginning and ending at substantially the same relative position of said rotating element, and means for releasing the action of said brake element when said traveling element is moved to the starting position, substantially as described.

40 33. The combination with a rotating member and a traveling member propelled thereby, and a brake member of a normally inoperative brake unlatching mechanism for the rotating member, movable periodically in opposite directions by the said rotating and traveling members respectively, the said mechanism being adapted to unlatch said

brake member after failure of the said traveling member to move said unlatching mechanism, the beginning and ending of said movement of said unlatching mechanism due to the action of the rotating member, occurring at substantially the same position of the said rotating member, and means for resetting said brake member by movement of said traveling member to the starting position, substantially as described.

34. In a talking machine comprising a rotating element, a feeding element and a brake element, an oscillating element frictionally fed by said feeding element and periodically repositioned in exact relation to said feeding element, said repositioning occurring at substantially the same relative position of the said rotating element.

35. In a talking machine comprising a rotating element, a feeding element and a brake element, an oscillating element frictionally fed by said feeding and periodically repositioned in exact relation to said feeding element, an unlatching member operated synchronously with said rotating element and adapted to interfere with said oscillating element to cause unlatching of said brake element, the beginning of said interference, and end of said repositioning occurring at substantially the same relative position of the rotating element, substantially as set forth.

36. In a talking machine comprising a rotating element, a feeding element and a brake element; a brake releasing element cooperating with said feeding element, and a repositioning element cooperating with said rotating element to periodically reposition said brake releasing element backward in relation to the feed, said repositioning element coacting on said brake releasing element after one or more complete rotations of the rotating element, substantially as described.
